FASTENER GUIDING ATTACHMENT FOR
SEWING MACHINESAlbert M. Schweda, Chicago, Ill., assignor to
Union Special Machine Company, Chicago, Ill.,
a corporation of Illinois

Application March 31, 1950, Serial No. 153,128

10 Claims. (Cl. 112—136)

1

This invention pertains to sewing machines, and in one of its more specific aspects, to a sewing machine attachment mechanism adapted to guide elements of a slide fastener unit disposed along a line transverse to a line of stitching in the course of forming the stitching by the sewing machine needle and associated devices in a piece of work that includes the fastener unit.

While the mechanism of this invention is adapted to be advantageously employed in stitching together various arrangements of parts including a fastener unit in a piece of work, it is particularly useful in simultaneously sewing a waistband on a pair of trousers and securing an end of a slide fastener strip unit in place between the edge of the waistband and the edge of the main trouser body. At the time that the waistband is secured in such an arrangement of parts, the slide fastener unit is disposed transverse to the line of feed, that is, transverse to the line of stitching being formed by the sewing machine needle and associated elements, and is positioned between the waistband parts as the waistband passes the needle.

Experience has demonstrated that unless conventional metallic fastener elements of the fastener unit are properly guided as they are moved past the needle, the needle may strike one of the fastener elements, and as a consequence, the needle oftentimes is damaged or broken. Even if the needle is only slightly burred as a result of striking a fastener element, it will not thenceforth coact with other parts in the formation of proper stitches. This necessitates replacement of such needles and costly delays in production. Also, it is apparent that needle breakage due to striking a fastener element may endanger the operator.

The present invention obviates the foregoing difficulties as it properly guides fastener elements so as to permit the sewing machine needle to stitch across the fastener unit without striking any of such elements. To this end, the guiding mechanism of the invention comprises a device including a finger so constructed and arranged as to be readily swung into or out of service immediately in advance of the needle for guiding the fastener elements at the proper time in the course of forming stitches across the unit. The finger, when in operative position, engages and guides adjacent fastener elements, but permits the needle to pass between those elements. The device is adapted to be placed into and out of service at the will of the operator, and is intended to be in active service only for the interval or a portion of the interval of time during which the fastener unit is being fed past the needle.

2

At other times, the device is swung to an inactive or inoperative position away from the stitch-forming devices, thereby permitting the carrying out of conventional sewing operations without interfering with or obstructing the work or retarding normal operations.

A primary object of the invention is to expedite the joining together of a slide fastener unit and other parts along a line across the fastener unit.

Another object of the invention is to provide a sewing machine attaching mechanism adapted to facilitate the formation of a line of stitches across a slide fastener unit in the course of stitching together parts of a piece of work including the fastener unit.

Another object of the invention is to provide a sewing machine slide fastener guiding attachment that is adapted to be connected directly to a sewing machine presser bar or presser foot shank and movable therewith, or be attached to the sewing machine head.

Another object of the invention is to provide an attaching mechanism of the character indicated, that is adapted to be readily placed into and out of active service at the will of the operator.

Another object of the invention is to minimize the possibility of damage or breakage to a sewing machine needle or associated devices in the course of forming stitches across a slide fastener unit.

The invention has for another object the provision of a sewing machine slide fastener guiding attachment that may be readily and quickly mounted on or removed from a sewing machine.

A further object of the invention is to provide a mechanism of the character indicated, that is adapted to perform its intended functions in an effective and trouble-free manner.

A further object of the invention is to provide a sewing machine slide fastener guiding mechanism that is simple and compact in design, sturdy in construction and reasonable in manufacturing and maintenance costs.

The foregoing objects, together with other objects, as well as the advantages obtainable by the practice of this invention, will be readily understood by persons skilled in the art upon reference to the following detailed description, taken in conjunction with the annexed drawings, which respectively describe and illustrate a preferred arrangement of devices embodying the invention.

In the drawings:

Figure 1 is a view in front elevation of a flat bed sewing machine having an arrangement of devices embodying the invention operatively associated therewith, certain parts that are not

essential to a full understanding of the invention being omitted, and certain other parts being broken away for better illustration;

Figure 2 is an enlarged view in end elevation of the apparatus of Figure 1, as seen from the left thereof;

Figure 3 is an enlarged view taken along line 3—3 of Figure 1, another relative position of certain of the depicted parts being represented by dot-dash lines;

Figure 4 is a view in enlargement of certain parts shown in Figure 3 in association with certain other parts;

Figure 5 is a front elevation view of a bracket and several parts carried thereby;

Figure 6 is a rear elevation view of Figure 5;

Figure 7 is a top plan view of one preferred form of fastener guiding device;

Figure 8 is an enlarged fragmentary view of Figure 3, and shows one relative position of certain parts in the course of feeding a piece of work through the sewing machine;

Figure 9 corresponds to Figure 8 and shows another relative position of the parts illustrated therein;

Figure 10 is an enlarged view in vertical cross section taken along line 10—10 of Figure 8;

Figure 11 corresponds to Figure 7 and illustrates another form of fastener guiding device;

Figure 12 is a view in front elevation of a portion of a modification of the invention; and

Figure 13 corresponds to Figure 12 and illustrates a portion of another modification of the invention.

Referring now to the drawings wherein like reference numerals denote corresponding parts throughout the several views, and more particularly to Figures 1 and 2, I have illustrated therein a flat bed type sewing machine, generally indicated by numeral 15 and comprising a base 16, the top of which is planar and constitutes a work support 17. Extending upwardly of the base is a hollow standard 18 that carries an integral hollow overhanging arm 19 having a depending head 20. Vertically reciprocable within head 20 is a needle bar 21 to which is removably attached a conventional needle 22 (Figure 10). A sewing machine of this general type is disclosed in F. F. Zeier Patent 1,843,188, entitled "Sewing Machine," to which reference may be had for an understanding of an arrangement of devices, not shown herein, for driving needle 22.

Parallel to needle bar 21 is a presser bar 25 that carries an open-toed presser foot 26 at its lower end. As is best shown in Figures 8 and 9, the presser foot is provided with an elongated slot 27 that extends rearwardly of its front edge 28. Mounted on overhanging arm 19 for yieldingly urging presser bar 25 and, therefore, presser foot 26 downwardly is a presser mechanism 29 which includes a horizontally disposed leaf spring 30. One end of the leaf spring is anchored to the overhanging arm by a stud (not shown). A thumb nut 31 engages a threaded vertical stem 32 which is attached to overhanging arm 19 and extends through a central aperture in the leaf spring. Reference may be had to F. A. Kucera Patent 2,103,470, entitled "Presser Mechanism for Sewing Machines," for further details as to the construction and operation of the presser mechanism herein illustrated.

A feed dog 33 is positioned in base 16 directly below presser foot 26, and is encompassed by a throat plate 34 (Figure 3). The feed cog is preferably actuated by a mechanism 35 of the four-

motion type that may be the same as or similar to the feeding mechanism illustrated and described in A. J. Wohlpert Patent 1,817,727, entitled "Feeding Mechanism for Sewing Machines."

The sewing machine may be mounted in the usual manner on a horizontal top 36 of a suitable supporting structure not otherwise shown. Top 36 is provided with a through aperture 37.

An arrangement of devices that constitutes a recommended form of fastener guiding attachment mechanism constructed in accordance with this invention will now be described, reference being had initially to Figures 1, 2, 5 and 6. In this connection, there is shown a support or bracket 40 that includes a lower arm 41 and an upper arm 42. The lower arm has an opening 43 for the reception of presser bar 25 and is secured to the presser bar by set screws 44. This arrangement permits of ready angular and vertical adjustment of the bracket with respect to the presser bar. An opening 45, in upper arm 42, accommodates the upper end of a post or stud 46 that is connected to the bracket in parallel relation to the presser bar by set screws 47 which permit of angular and vertical adjustment of the post with respect to the bracket. The post is provided at its lower end with an integral member or head 50 that has an upper camming surface 51. An adjustable stop 52 consists of a horizontal arm 53 and a depending stop arm 54. As is shown in Figure 6, arm 53 is positioned in a horizontal guide groove 55 formed in the bracket, and is adjustable with respect to the bracket as allowed by a screw 56 which extends through a slot 57 in arm 53. Secured to the bracket and projecting downwardly therefrom is a stop pin 58.

A unitary fastener guiding device, generally indicated by numeral 60 and best shown in Figures 1, 2 and 7, is pivotal with respect to and movable along post 46. This device includes a hub 61 coaxial with post 46 and having a camming under surface 62 which is complementary to camming surface 51 of member 50; a generally hook-shaped member 63 that terminates in a tapered wedge-like guide finger 64; and an arm 65 that projects to the side of the axis of the hub opposite member 63. The arm has a spring-receiving first opening 66 and a second opening 67 adjacent its free end.

A helical compression spring 70 coaxial with post 46 bears at one end against a washer 71 that rests on hub 61, and at its other end against a collar 72 which is affixed to the post by a set screw 73. The axial position of the collar with respect to the post determines the loading on spring 70. A spring 75 is connected to arm 65 through opening 66 and to the bracket by a screw 76. Spring 75 is stressed in tension and normally urges device 60 in a counter-clockwise direction with respect to post 46 to the position shown in Figure 9. Stop pin 58 limits such clockwise movement of device 60 with respect to the post.

Fastener guiding device 60 is adapted to be rotated about post 46 in a clockwise direction, from the position shown in Figure 9 to that shown in Figure 8, through the coaction of devices that will next be described. Referring to Figures 1 and 2, such devices include a block 77 supported on top 36 and having a vertical through aperture 78 that is in alignment with aperture 37 in the top. A pulley bracket 80, consisting of a base 81 and a pair of parallel

spaced arms 82, is attached to the block by screws 83. Disposed between bracket arms 82 and rotatable about a pin 84 carried by these arms is a pulley 85.

An inverted U-shaped bracket 86 is mounted against the under surface of top 36 and includes a pair of spaced parallel arms 87 which support a rock shaft 90. A collar 91 is attached to each end of the rock shaft to prevent axial movement of the shaft. A pair of blocks 92 and 93 embrace the rock shaft intermediate bracket arms 87 and are angularly and axially adjustable with respect to the rock shaft through the medium of set screws 94 and 95, respectively. Extending radially of block 92 is a rod 96. A flexible cable 97 is connected at one end to the free end of rod 96, extends upwardly through apertures 37 and 78, passes over pulley 85, and is connected at its other end to arm 65 by a bolt 98 which extends through arm opening 67 and has a nut 99 (Figure 2). A second rod 100 is attached to block 93 by a set screw 101 (Figure 1). A knee pad 102 is adjustably attached to the lower end portion of rod 100 by a set screw 103.

I have shown in Figures 8 and 9 a portion of the fabric of a trouser body 105 including a fly strip 106. Secured to strip 106 by rows of stitching 107 is a conventional slide fastener unit 108 consisting of a tape stringer 109 and a series of fastener elements 110. A preformed fabric unit 111 (Figures 9 and 10) comprises a waistband 112 stitched to a waistband lining strip 113 and to a waistband reinforcing strip 114, as indicated at 115. Reinforcing strip 114 is superposed on lining strip 113, a portion 116 of the lining strip being folded over the reinforcing strip and secured thereto by a row of stitching 117. In Figure 9 there is shown a belt loop 118 secured to the waistband.

For the purpose of briefly outlining the mode of operation of the illustrated apparatus, it is assumed that the same is being used to join fabric unit 111 to trouser body 105 and that fastener unit 108 and the other parts of the piece of work are in the relative position shown in Figure 8. The line of stitching being formed by the sewing machine is indicated at 120, and as is shown in Figure 9, this line of stitching is transverse to the fastener unit. It is further assumed that the parts of the guiding mechanism are in the relative position shown in Figure 9. This is the normal position of the parts of the guiding mechanism due to the action of spring 75. With the parts in this position, fastener guiding device 60 has been swung and raised with respect to post 46 due to the action of spring 75 and the interaction of camming surfaces 51 and 62 against the downward thrust of spring 70.

In the course of stitching unit 111 to body 105, the guiding mechanism is maintained out of service until fastener elements 110 approach the needle. At that time the operator presses pad member 102 with his knee, imparting counter-clockwise pivotal movement to rock shaft 90 (Figure 1) and actuating flexible cable 97, thereby imparting clockwise rotation to guiding device 60 about post 46 against the action of spring 75 to the extent allowed by stop arm 54. Simultaneous with the foregoing, device 60 is moved downwardly with respect to post 46 due to camming surfaces 51 and 62 and the action of compression spring 70. It will thus be noted that actuation of the knee pad member 102, as indicated, results in a combined downward and

pivotal movement of guiding device 60 and, therefore, finger 64. The finger is so configured and arranged that as it moves downwardly and arcuately, it enters in the space between adjacent fastener elements 110 and aligns this space with the needle. As the work is continued to be fed through the sewing machine, the needle passes between the aforementioned adjacent fastener elements. After the fastener unit and associated fabrics have been fed past the needle, the operator releases knee pressure on pad member 102, whereupon the parts of the attachment mechanism are returned to inactive position (Figure 9) by spring 75.

There is shown in Figure 11 a modified form of fastener guiding device 120 that may be advantageously employed in lieu of earlier described fastener guiding device 60. Device 120 comprises a hub 121 which, as in the case of hub 61, has a camming under surface (not shown) that is complementary to camming surface 51 of member 50. Integral with the hub is an arm 122 that extends to one side of the axis of the hub and has a first opening 123 for receiving an end of spring 75, and a second opening 124 for connection to cable 97 by means of bolt 98. Also integral with the hub is a relatively short arm 125 extending to the side of the axis of the hub opposite arm 122. A hook-shaped member 126, that may be the same in configuration as member 63, terminates in a tapered guide finger 127. Member 126 is attached to short arm 125 by a screw 128 which extends through a slot 129 in the member. As will be apparent from an examination of Figure 11, the illustrated construction permits of lateral and angular adjustment of member 126 relative to the hub.

The modification of the invention shown in Figure 12 contemplates securing the fastener guiding attachment mechanism to the sewing machine head instead of to the presser bar. To this end, a bracket 130, corresponding to earlier described bracket 40, includes a lower arm 131 and an upper arm 132, the latter arm being connected to post 46 by set screws 47. The bracket has an additional arm 133 for connection to sewing machine head 20 by one or more screws 134. The mechanism is otherwise the same as in the earlier described construction.

When the construction shown in Figure 12 is used, bracket 130 and post 46 remain stationary relative to the sewing machine frame. Fastener guiding device 60 is, however, movable axially and angularly with respect to the post into and out of active position in the manner described.

There is shown in Figure 13 a further modification of the invention employing another form of bracket or support 135 that includes upper and lower arms 136 and 137, respectively. Integral with the lower arm is a depending tubular member 138 coaxial with presser bar 25 and constituting an elongated shank for and pivotally connected to presser foot 26, as indicated at 139. A screw 140, for attaching tubular member 138 to the presser bar, permits of angular and axial adjustment of the tubular member with respect to the presser bar. The construction shown in Figure 13 is otherwise the same as in the first described embodiment of the invention. Also, it will be noted that in this modification the fastener guiding attachment mechanism is reciprocable with the presser bar.

From the foregoing, it is believed that the construction, operation, and advantages of my present invention will be readily comprehended

by persons skilled in the art. It is to be clearly understood, however, that various changes in the apparatus set forth above may be made without departing from the scope of the invention, it being intended that all matter contained in the description or shown in the drawing shall be interpreted as illustrative only and not in a limiting sense.

I claim:

1. In a sewing machine attachment mechanism that is adapted to guide fastener elements of a slide fastener unit disposed along a line generally transverse to a line of stitching in the course of forming such stitching by the sewing machine needle and associated elements in a piece of work which includes the fastener unit, a support adapted to be attached to the sewing machine, a post carried by the support, a fastener guiding device including a hub pivotally connected to and movable along the axis of the post, said device including a finger having a free end, resilient means normally maintaining the device in a predetermined angular and axial position relative to the post to position the free end of the finger away from the needle and above the work, and means connected to the device for moving the device in one direction about its pivotal connection with the post and in a corresponding direction along the axis of the post against the action of the resilient means to swing the free end of the finger toward the work and to the side of the needle opposite previously formed stitches.

2. In an attachment mechanism for a sewing machine that includes a reciprocable presser bar, a needle and associated stitch-forming elements, which mechanism is adapted to guide fastener elements of a slide fastener unit disposed along a line generally transverse to a line of stitching in the course of forming such stitching by the sewing machine in a piece of work which includes the fastener unit, a support adapted to be attached to the presser bar for reciprocation therewith, a post carried by the support in spaced and substantially parallel relation to the presser bar, a fastener guiding device including a hub pivotally connected to and movable along the axis of the post, said device including a finger having a free end, resilient means normally maintaining the device in a predetermined angular and axial position relative to the post to position the free end of the finger away from the needle and above the work, said means including a spring connected to the support and to the device, and means connected to the device for moving the device in one direction about its pivotal connection with the post and in a corresponding direction along the axis of the post against the action of the resilient means to swing the free end of the finger toward the work and to the side of the needle opposite previously formed stitches.

3. In an attachment mechanism for a sewing machine that includes a reciprocable presser bar, a needle and associated stitch-forming elements, which mechanism is adapted to guide fastener elements of a slide fastener unit disposed along a line generally transverse to a line of stitching in the course of forming such stitching by the sewing machine in a piece of work which includes the fastener unit, a support adapted to be attached to the presser bar for reciprocation therewith, said support comprising a tubular presser foot shank coaxial with the presser bar and a bracket extending upwardly and to one side of the shank, a post carried by the end of

the bracket remote from the shank in spaced and substantially parallel relation to the needle, a fastener guiding device including a hub pivotally connected to and movable along the axis of the post, said device including a finger having a free end, resilient means normally maintaining the device in a predetermined angular and axial position relative to the post to position the free end of the finger away from the needle and above the work, said means including a spring connected to the support and to the device, and means connected to the device for moving the device in one direction about its pivotal connection with the post and in a corresponding direction along the axis of the post against the action of the resilient means to swing the free end of the finger toward the work and to the side of the needle opposite previously formed stitches.

20 4. In a sewing machine attachment of the class described, a support adapted to be attached to the sewing machine, a post carried by the support, a fastener guiding device including a hub pivotally connected to and movable along the post, said device including a finger having a free end, resilient means normally maintaining the device in a predetermined angular and axial position relative to the post, said means including a spring connected to the support and to the device, and means connected to the device for moving the device in one direction about its pivotal connection with the post and in a corresponding direction along the post against the action of the resilient means, said last-mentioned means including a spring normally urging the device in said corresponding direction.

5 5. In a sewing machine attachment of the class described, a support adapted to be attached to the sewing machine, a post carried by the support, a fastener guiding device including a hub pivotally connected to and movable along the post, said device including a finger having a free end, a spring connected to the support and to the device for normally imparting pivotal movement to the device with respect to the post in one direction, camming means cooperating with the hub for effecting corresponding movement of the device along the post in response to pivotal movement of the device with respect to the post in said one direction, and means connected to the device for imparting reverse pivotal and axial movements to the device with respect to the post against the action of the spring, said last-mentioned means including a spring normally urging the device in said reverse direction.

60 6. In a sewing machine attachment of the class described, a support adapted to be attached to the sewing machine, a post depending from the support, a fastener guiding device pivotally connected to and movable along the post, said device comprising a hub coaxial with the post and a finger secured to the hub and having a free end located below and to one side of the axis of the hub, a spring connected to the support and to the device for normally imparting pivotal movement to the device with respect to the post in one direction, camming means cooperating with the hub for effecting upward movement of the device along the post in response to pivotal movement of the device with respect to the post in said one direction, and means connected to the device for moving the device in a reverse direction about its pivotal connection with the post and in a downward direction along

the post against the action of the spring, said last-mentioned means including a spring normally urging the device in said downward direction.

7. In a sewing machine attachment of the class described, a support adapted to be attached to the sewing machine, a post carried by the support, a fastener guiding device including a hub pivotally connected to and movable along the post, said device including a finger having a free end, a spring connected to the support and to the device for normally imparting pivotal movement to the device with respect to the post in one direction, a member secured to the post, the member and the device having cooperative camming surfaces for effecting corresponding movement of the device along the post in response to pivotal movement of the device with respect to the post in said one direction, means connected to the device for imparting reverse pivotal and axial movements to the device with respect to the post against the action of the spring.

8. In a sewing machine attachment of the class described, a support adapted to be attached to the sewing machine, a post depending from the support, a fastener guiding device pivotally connected to and movable along the post, said device comprising a hub coaxial with the post and a finger having a free end carried by the hub, a member secured to the post below the hub, the member and the device having cooperative camming surfaces for effecting upward movement of the device along the post in response to corresponding pivotal movement of the device with respect to the post in said one direction, and means connected to the device for moving the device in a reverse direction about its pivotal connection with the post and in a downward direction along the axis of the post against the action of the spring, said last-mentioned means including a spring normally urging the device in said downward direction.

9. In a sewing machine attachment of the class described, a support adapted to be attached to the sewing machine, a post depending from the support, a fastener guiding device pivotally connected to and movable along the post, said device comprising a hub coaxial with the post, a finger secured to the hub and having a free end located below and to one side of the axis of the hub, said finger being laterally and angularly adjustable with respect to the hub, and an arm connected to the hub and disposed to the other side of the axis of the hub, a spring connected

to the support and to the arm for normally imparting pivotal movement to the device with respect to the post in one direction, camming means cooperating with the hub for effecting upward movement of the device along the post in response to pivotal movement of the device with respect to the post in said one direction, means connected to the device for moving the device in a reverse direction about its pivotal connection with the post and in a downward direction along the axis of the post against the action of the spring, said last-mentioned means including a spring normally urging the device in said downward direction, and stop elements carried by the support for limiting pivotal movement of the device with respect to the post in either direction.

10. In an attachment for a sewing machine that includes a presser bar, a support comprising a tubular member adapted to receive and be attached to the presser bar and a bracket carried by the tubular member, a post depending from the bracket, said post being spaced from and parallel to the tubular member, a fastener guiding device pivotally connected to and movable along the post, said device comprising a hub coaxial with the post and a finger secured to the hub and having a free end located below and to one side of the axis of the hub, a spring connected to the support and to the device for normally imparting pivotal movement to the device with respect to the post in one direction, camming means cooperating with the hub for effecting upward movement of the device along the post in response to pivotal movement of the device with respect to the post in said one direction, and means connected to the device for moving the device in a reverse direction about its pivotal connection with the post and in a downward direction along the post against the action of the spring, said last-mentioned means including a spring normally urging the device in said downward direction.

ALBERT M. SCHWEDA.
